(57) **CLAIM**

The ornamental design for a pedestal for wireless signal transmission device, as shown and described.

DESCRIPTION

FIG. 1 is a perspective view of a pedestal for wireless signal transmission device in accordance with our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a perspective reference view of the pedestal when pivotally connected to a wireless signal transmission device such as Wireless Access Point (WAP), wireless router, or Customer Premise Equipment (CPE).

There is no design feature to be shown in the bottom plan view of the pedestal, and thus the bottom plan view of the pedestal is omitted therein. The broken lines immediately adjacent the claimed areas represent the bounds of the claimed design while all other broken lines are directed to environment and are for illustrative purposes only. The broken lines form no part of the claimed design.

1 Claim, 5 Drawing Sheets
